DISPLAY DEVICE

John V. Horr, North Tarrytown, N. Y., assignor to
Einson-Freeman Co., Inc., Long Island City,
N. Y., a corporation of Delaware

Application January 22, 1944, Serial No. 519,273

2 Claims. (Cl. 40—152.1)

My present invention relates generally to display devices.

A general object of the invention is to provide an improved structure by means of which a display unit may be conveniently and safely transported from place to place, and may be effectively exhibited, when desired, on an easel-like support. The present structure is so designed that the element or elements of which it is composed will normally serve as a compact and secure enclosure for the display unit, and may be adjusted, when desired, to define a rugged supporting structure in the form of a display easel. The structure is preferably composed of a single element of relatively stiff cardboard or the like.

While certain phases of my invention are not necessarily restricted to any particular type of use, the construction is primarily intended and is peculiarly adapted for the transportation and exhibition of a display unit which consists of a series of posters of educational or informative character. For example, the present device has proven to be particularly useful in the transportation and display, to members of the armed forces in the field, of posters of substantial size, e. g., about 3' in width and 4' in length, or larger.

The structure consists essentially of a backing element on which the display unit is arranged, and a cover element which normally overlies the display unit. The backing and cover elements are of relatively stiff cardboard or the like, and normally define a compact substantially flat enclosure which conceals and protects the display unit and permits it to be readily transported from place to place. The cover element has its top end hinged to the top edge of the backing element so that it may be swung upwardly and around to serve as a rear prop which supports the backing element as an inclined easel.

One of the features of my invention lies in the provision of a special type of fastening member which is carried by one of said elements and is adapted to extend either around the backing and cover elements to retain the device in closed condition or across the gap between the backing and cover elements to serve as a brace when the device is set up as an easel. In the preferred embodiment, the fastening member consists of a tie or string-like piece, which is fixed at one end and has the other end free, the other element of the structure being provided with a supplemental anchorage with which the free end of the tie may be releasably engaged. One such fastening member may be sufficient, but a more efficient and staunch construction results from the em-

ployment of two, or possibly more, of such fastening members.

Where the display unit is in the form of a series of superposed posters, composed of relatively flexible material such as paper or the like, the stack of posters is secured along its upper margin to the backing element, so that when the device is set up as an easel the posters may be successively swung upwardly and rearwardly to lie face down against the cover element. In a structure of this kind, it is a further feature of my invention to provide each poster, on its rear face, with descriptive indicia which relate to the next successive poster and which are so arranged that they appear in upright condition when viewed from the rear of the device. This permits the posters to be used for illustrative purposes in connection with an oral lecture, the lecturer standing behind the device so as not to impede a continuous clear view of the successive posters.

I achieve the foregoing objects and advantages, and such other objects and advantages as may hereinafter appear or be pointed out, in the manner illustratively exemplified in the accompanying drawing in which:

Figure 1 is a perspective view of a display device of the present character, shown in closed condition and viewed from the rear;

Figure 2 is an enlarged cross-sectional view taken substantially along the line 2—2 of Figure 1;

Figure 3 is an enlarged cross-sectional view taken substantially along the line 3—3 of Figure 1;

Figure 4 is a perspective view of the device adjusted into the form of an easel; and

Figure 5 is a view similar to Figure 4 illustrating its manner of use.

In the embodiment illustrated, a substantially rectangular backing element 10, composed of relatively stiff cardboard or the like, is hinged along its top edge to the top edge of a similar substantially rectangular element 11 which constitutes a cover element. The hinged relationship may be established in any desired way, and it has proven satisfactory to form the elements 10 and 11 of a single blank of material, a narrow intermediate panel 12 connecting these elements along their top edges.

Carried by the backing element 10 is a display unit 13 which I have illustratively shown in the form of a group of posters. These posters are composed of relatively flexible material, such as paper, and they are arranged in the form of a stack which is secured along its upper margin

to the backing element 10. This securement may be achieved in any desired manner, and I have chosen to illustrate the employment of a bracing or retaining strip 14 extending along the upper margin of the stack of posters, and three attachment devices 15 extending through the strip 14, through the stack of posters and into permanent engagement with the backing element 10.

If desired, the display unit may comprise an auxiliary backing panel 16 of relatively rigid character which underlies the group of superposed posters.

The side margins of the backing element 10 are preferably provided with inturned flaps 17, and the bottom or free edge is preferably provided with a corresponding inturned flap 18. These flaps serve to rigidify the structure along its edges, and they also serve to cover and thereby shield the free edges of the posters forming the display unit whenever the device is in closed condition.

A similar set of inturned flaps 19 may be advantageously formed along the free edges of the cover element 11, for rigidifying or stiffening purposes.

Carried by the elements 10 and 11 on their outer faces are complementary parts of a fastening means which fulfills a unique function in connection with the present device. I have illustratively shown the element 10 provided with disk-like buttons or anchorages 20 arranged adjacent to the lower corners of the device; and I have shown the cover elements 11 provided with similar anchorages 21 which are correspondingly positioned. A tie or string-like element 22 is fastened to each of the anchorages 20, leaving its opposite end free.

When the unit is closed, as shown in Figures 1, 2 and 3, each tie element 22 is caused to extend around the backing and cover elements and into engagement with the corresponding anchorage. A preferred procedure lies in extending the element 22 down around the bottom edges of the device, thence into interengagement with the anchorage 21, then back again around the side edges of the device into final engagement with the original anchorage 20.

I have illustratively shown two such fastening means, but it will be understood that only a single one might be deemed to be sufficient, under certain circumstances, while more than two might be deemed to be desirable under other circumstances.

To facilitate the transportation of the device, the backing element 10 is preferably provided with a hand-hole 23 so that the device may be carried under the arm of the user, in a substantially vertical plane. During this transportation, it will be observed that the enclosed display unit is completely covered and shielded.

When the device is ready to be used for exhibition purposes, the tie elements 22 are disengaged, and the cover element 11 is swung upwardly and around until the parts assume the relationship shown in Figure 4. It will be noted that the cover element now serves as a rear prop which supports the backing element 10 as an inclined display easel. Each tie element 22 is then caused to extend across the gap between the backing and cover elements, and is re-engaged with its complementary anchorage. Assuming, for example, that each tie element 22 is permanently secured at one end to one of the anchorages 20 on the backing element 10, the free end is caused to engage around the corresponding anchorage 21 on the cover element 11.

Each fastening member 22 thus serves as a brace for the rear prop when the device is set up as an easel.

By arranging the parts as shown in Figure 4, the posters are exposed to view, and to indicate certain features of the present improved construction, I have designated the uppermost poster, in Figure 4, as "Poster No. 1." The posters may be successively exhibited by swinging each poster upwardly and around, over the apex of the easel structure into a position where it lies face down upon the cover element 11. This brings the next succeeding poster into view. Obviously, during this procedure, the flaps 17 and 18 are turned outwards, as indicated in Figure 5.

One of the features of my invention lies in providing on the back surface of each poster certain markings or indicia which relate to the next successive poster, these markings being so arranged that they are visible in upright condition from the rear of the device. This permits a lecturer to stand behind the structure and to discuss the successive posters with the aid of the descriptions which are successively presented to view, the exhibited posters being at all times freely exposed to the view of an audience positioned in front of the device.

Thus, in Figure 5, I have indicated Poster No. 5 by the reference numeral 24 and have shown this poster in the process of being swung upwardly and rearwardly in order to bring "Poster No. 6" into view. It will be noted that on the rear face of the poster 24 there is descriptive material or indicia 25 which relates, not to "Poster No. 5," but to "Poster No. 6." It will also be observed that the indicia 25 are arranged in such a relationship that they appear in upright condition to a person standing behind the device.

After all the posters have been exhibited, they may all be swung back into stacked relationship on the backing element 10, the flaps 17 and 18 are then brought into the positions shown in Figure 4; the tie elements 22 are disconnected, and the cover element 11 is then swung forwardly again into its normal covering relationship to the display unit. The fastening members 22 are then again adjusted around the backing and cover elements to serve as the means for retaining these elements in normal closed condition.

The device thus affords a simple yet highly efficient unit for conveniently transporting and exhibiting display material. Being composed essentially of cardboard or the like, it is inexpensive to manufacture, simple in structural nature, and relatively light in weight. By virtue of the special fastening member or members, as hereinbefore described and illustrated, the device may be quickly and conveniently tied or secured in a normally closed condition, in which the contents are well shielded and protected, or it may be set up, without the aid of or necessity for any special platform or other pedestal or structure, to form a staunch thoroughly braced display easel. The device is rugged in structural character, can withstand relatively rough handling, and has proven highly useful in the dissemination of educational information to the armed forces in the field.

In general, it will be understood that the details herein described and illustrated to explain the general nature of the invention may be modified by those skilled in the art without departing from the spirit and scope of the invention as expressed in the appended claims.

Having thus described my invention and illus-

trated its use, what I claim as new and desire to secure by Letters Patent is:

1. A display device comprising a stiff backing element, a display unit thereon, a stiff cover element adapted to overlie said display unit when the device is closed, said cover element having its top edge hinged to the top edge of the backing element so that it may be swung upwardly and around to serve as a rear prop which supports the backing element as an inclined easel for said display unit, a fastening member carried by one of said elements, and a complementary anchorage carried by the other of said elements, said fastening member being adapted to extend either around the backing and cover elements to retain the device in closed condition or across the gap between the backing and cover elements to serve as a brace when the device is set up as an easel, each of said fastening member and complementary anchorage being secured to the outer face of the element carrying it.

2. A display device comprising a stiff backing

element, a display unit thereon, a stiff cover element adapted to overlie said display unit when the device is closed, said cover element having its top edge hinged to the top edge of the backing element so that it may be swung upwardly and around to serve as a rear prop which supports the backing element as an inclined easel for said display unit, a fastening member carried by one of said elements, and a complementary anchorage carried by the other of said elements, 5 said fastening member being adapted to extend either around the backing and cover elements to retain the device in closed condition or across the gap between the backing and cover elements to serve as a brace when the device is set up as an easel, each of said fastening member and complementary anchorage being secured to the outer face of the element carrying it, said fastening member comprising a flexible tie having one end fixed and 10 the other end free, and said anchorage being adapted to be releasably engaged by said free end.

JOHN V. HORN.
